FREDERICK M. DOAK, OF SAN FRANCISCO, CALIFORNIA.

WATER-FLUME.

1,052,901.

Specification of Letters Patent. Patented Feb. 11, 1913.

Application filed July 25, 1912. Serial No. 711,447.

To all whom it may concern:

Be it known that I, FREDERICK M. DOAK, a citizen of the United States, residing in the city and county of San Francisco and 5 State of California, have invented certain new and useful Improvements in Water-Flumes, of which the following is a specification.

The hereinafter described invention relates to that class of water flumes comprising a plurality of open metallic sections, the ends of which are united and the joined sections supported by means of a suitable frame erected along the line of the flume. 10 Ordinarily, the flumes of this character are formed of a number of short metallic sections, each approximately two feet in length, requiring that a large number of the same be united to form a flume section of 15 any given length, as, for instance, in erecting thirty-two feet of flume it is required to make fifteen joints or connection, or in one mile of flume with two foot sections there are two thousand six hundred and thirty-nine joints, which materially adds to the 20 field work and time required to properly construct a flume of any considerable length.

The object of the present invention is to 25 facilitate the erection of metallic water flumes, to reduce the expense incident thereto, to so connect the sections as to allow for free expansion thereof, and in general to produce a stronger, more durable flume and one less liable to leakage than with the open metallic flume as at present constructed.

With the present invention the open metallic flume sections are made in lengths of sixteen feet, so that in each mile of constructed flume there exists three hundred and thirty joints or flume sections, as against two thousand six hundred and thirty-nine joints with two foot standard sections, with the result that the field work of erecting the 45 flume is reduced to a minimum.

To comprehend the invention reference should be had to the accompanying drawings, wherein—

Figure 1 is a broken plan view of the 50 improved flume. Fig. 2 is a cross sectional view taken on line α — α Fig. 1 of the drawings. Fig. 3 is a broken side view of the flume.

In the drawings, the numerals 1 and 2 are 55 used to designate adjacent metallic flume sections each approximately sixteen feet in

length, and three feet in width at the top thereof, the forward end of section 1 overlapping the adjacent end of section 2 for a distance sufficient to establish a closure at 60 such point, say—two inches, more or less. The upper side edge of each flume section is united or riveted to the flange a of an angle iron reinforcing strip 3, which extends the length of each flume section to within a distance of the ends thereof equal to the overlap of adjacent sections, so that when the sections are properly placed relative to each other the ends of adjacent angle irons 3 65 abut. The flume is held between and supported by a suitable frame structure, comprising in the present instance the upright posts 4, tie braces 5, and the spaced longitudinally disposed stringers 7. On the said stringers 7 rest the outwardly extended flange b of the angle irons 3, so that the entire weight of the flume as constructed falls on and is taken care of by the frame structure, and transverse of said structure at each joint or union of adjacent flume sections is 70 provided a channel iron beam or bridge piece 8, the ends of which rest on the flange b of the angle iron 3 and covers the abutting ends of said angle iron, which in turn 75 rest on the tie plate 9 fitted in the cut away portion 10 of the stringers 7, the said tie plate breaking the joint of the abutting ends of the angle irons and with the angle irons being united to the channel iron beam 8 by means of the securing bolts 11. The 80 outer ends of the beam 8 rest on a flushing plate 12 which is equal in thickness to that of the flange b of the reinforcing angle irons 3, and the said beam with the plates 12 are secured to the longitudinal stringers 7 85 of the supporting frame structure by means of the lag-screws 13, the channel beam being thus held firmly in position relative to the supporting frame structure.

Under the described structural arrangement of the parts it is only required in assembling the flume to place the outwardly extended flange of the reinforcing angle irons on the side stringers of the frame structure, the abutting ends of said angle irons resting on the inserted tie plates 9, then arrange the channel beam 8 transverse of the supporting structure for the flume above the overlapping ends of adjacent flume sections, unite thereto the tie plates 105 and angle irons of adjacent flume sections by the bolts 11 and finally secure the channel 110

beam to the stringers 7 by means of the lag-screws 13. The parts are thus quickly and easily assembled and when in position the entire weight of the constructed open metallic flume is uniformly distributed throughout the supporting frame structure, and inasmuch as the overlapping ends of adjacent metallic flume sections are not interlocked or tied one to the other, the said sections are permitted free longitudinal expansion relative to one another, such expansion being a matter of importance on account of the climatic changes to which flumes of this character are subjected, as it provides against buckling of the sections and possible breakage at the joint union and the leakage which in such event take place.

By reason of the quick assembling of the parts permissible under this construction of the described flume system, there is a material gain in time and labor in the installation thereof and as the joint unions and the coupling features therefor are reduced to a minimum without in any manner impairing the strength of the flume, there is created a considerable reduction in the expense of the installation, and inasmuch as the weight of the flume is uniformly distributed throughout the supporting structure, the danger of sagging of the flume sections due to the length thereof is avoided.

Having thus described the invention what is claimed as new and desired to protect by Letters Patent is—

35 1. A water-way flume, the same comprising a supporting structure, a plurality of comparatively long metallic open flume sections held therein, the ends of adjacent sections overlapping, an angle iron reinforcing strip secured to the side edges of each flume section and resting on the supporting structure, and means for detachably-uniting each angle iron reinforcing strip to the supporting structure adjacent the transverse joint formed by the overlapping ends of the flume sections.

2. A water-way flume, the same comprising a supporting structure, a plurality of comparatively long metallic open flume sections held within the sphere of the supporting structure, the ends of adjacent flume sections overlapping, an angle iron reinforcing strip secured to the upper edges of each flume section and resting on the supporting structure, a tie plate on the said structure for breaking the joint between the abutting

ends of adjacent flume sections, a channel beam transversely disposed relatively to the supporting structure above the joint of adjacent flume sections, devices for connecting the tie plates and the ends of adjacent angle irons to the channel beam, and means for securing the said beam to the supporting structure.

3. A water-way flume, the same comprising a supporting structure, a plurality of comparatively long metallic open flume sections situated within the sphere of the supporting structure, the ends of adjacent sections overlapping, angle irons secured to the upper edges of each flume section for holding the same to the supporting structure, a beam transversely disposed relative to the said structure above the joint of adjacent flume sections, devices for uniting the angle irons of adjacent flume sections to the transverse beam, and means for securing the said beam to the supporting structure.

4. A water-way flume, the same comprising a supporting structure, a plurality of comparatively long metallic open flume sections held within the sphere of the supporting structure with the ends of adjacent sections overlapping, a longitudinally disposed angle iron reinforcing strip secured to the side edges of each flume section, said angle irons resting on the supporting structure to distribute uniformly thereon the weight of the flume sections, and means for uniting the abutting ends of the angle irons of adjacent flume sections to the supporting structure.

5. The combination with a suitable supporting structure, of a flume composed of a plurality of comparatively long open metallic flume sections held within the sphere of the said structure and the ends of adjacent sections overlapping, a beam transversely disposed relative to the supporting structure immediately above each of the overlapping joints of the flume sections, means for clamping the ends of adjacent flume sections to the transverse beam, and devices for securing the said beam to the supporting structure.

In testimony whereof I have signed my name to this specification in the presence of two subscribing witnesses.

FREDERICK M. DOAK.
